UNITED STATES PATENT OFFICE.

JONATHAN SCHARR, OF WARWICK, RHODE ISLAND.

WASHING-MACHINE.

SPECIFICATION forming part of Letters Patent No. 323,740, dated August 4, 1885.

Application filed November 12, 1883. (No model.)

To all whom it may concern:

Be it known that I, JONATHAN SCHARR, of Warwick, in the county of Kent and State of Rhode Island, have invented a new and useful Improvement in Washing-Machines; and I hereby declare the following to be a full, clear, and exact description of the same, reference being had to the accompanying drawings, forming part of this specification.

10 This invention has reference to that class of washing-machines in which the clothes are subjected to the action of pounders; and it consists in the peculiar and novel features of construction and arrangement whereby the

15 tub is rotated and air and soap and water are forced through the clothes by the reciprocating pounders to facilitate the washing of the clothes, as will be more fully set forth herein-after.

20 Figure 1 is a vertical view of the machine, partly in section, showing the tub in section. Fig. 2 is a side view of the machine, showing the clothes-wringer secured to the frame of the machine. Fig. 3 is a top view of the machine, partly in section. Fig. 4 is a sectional view of a conical open-ended pounder divided by a cross partition. Fig. 5 is a sectional view of a conical pounder, the open end of which is formed by three rings; and Fig. 6 is a sectional view of a conical pounder, the open end of which is divided by four angular partitions.

25 In the drawings, A is a firm standard, made of any suitable material, so as to firmly support the parts of the machine.

30 B is a wash-tub mounted on the spindle b, which rests in a suitable step on the frame, so as to support the tub and allow the same to rotate when filled or partly filled with water and clothes. The bottom of the tub is provided with the beveled gear b'. Across the machine is placed the shaft c, which is provided with the beveled pinion c', which gears into the beveled gear b', so that by rotating 40 the shaft c the tub will also be rotated. c² c² are cranks formed on the shaft c, and c³ c³ are the operating-cranks.

45 D D are the pounders. They are connected by the bent arms d d with the cranks c² c², the upper ends of the arms d, extending through 50 the slots d' in the frame A, form the guides

for the pounders D, by means of which they are guided vertically and are made to reciprocate vertically when the shaft c is turned.

E is a wringer, secured by means of brackets to the frame of the machine.

The pounders D are funnel-shaped sheet-metal cones. Their base is open, and when they enter the mass of water and clothes they bear down the cloth until the air is compressed 60 sufficiently to be forced through the clothes, and thereby the water and soap are forced through the clothes, so as to thoroughly cleanse the same. Such funnel-shaped pounders are well-known devices and have been constructed 65 in various forms. I divide the large open end of the pounder by partitions, the edges of which only come in contact with the clothes, and have, for the purpose of illustration, shown three modes of construction in Figs. 4, 5, and 6. 70

The operation of the machine is as follows: The clothes being placed into the tub and soap and water added thereto, the tub is revolved by turning the cranks c² c², and the pounders are reciprocated so as to force the air, water, 75 and soap through the clothes until they are thoroughly cleansed, which is accomplished in a very short time.

b² designates a hollow tapering projection, the lower end of which is flared out at right 80 angles, and the upper sides of which flared portions are secured about an orifice in the bottom of the tub B. The flared sides of the projection b² are secured to the under side of the tub, either by solder or in any other suitable 85 manner, so as to form a water-tight joint. This projection thus forms a part of the tub and extends vertically upward from the bottom thereof. The object of this projection is to prevent any contact of the pounders which are secured pivotally to the ends of the arms 90 d. As the pounders swing toward each other, they strike against the projection b², and are thus not only prevented from striking against each other, but are guided by said projection 95 toward the bottom of the tub.

To facilitate the action of the pounders on the clothes and prevent their lateral movement, I place the conical projection b² into the tub, and by making the same hollow it may form the 100 connection with the driving-gears, so that the tub may be readily lifted off the spindle b.

When the clothes are thoroughly washed, they are wrung on the wringer E and are ready to be dried.

The machine is so simple that any person 5 can easily operate the same, and it will wash clothes of any kind or size.

Having thus described my invention, I claim as new and desire to secure by Letters Patent—

The combination of the slotted frame A, carrying the shaft b, of the shaft c, mounted in 10 said frame and carrying the gear c', the rods

d, carrying the pounders D, the cranks c² c³, the tub B with its gear b' and the projection b², all of said parts being constructed and arranged to operate, as set forth.

In witness whereof I have hereunto set my hand.

JONATHAN SCHARR.
